ASSIGNORS TO WESTINGHOUSE ELECTRIC & MANUFACTURING COMPANY, A COR-
PORATION OF PENNSYLVANIA.

MOUNTING FOR SEWING-MACHINE MOTORS.

1,417,722.

Specification of Letters Patent. Patented May 30, 1922.

Application filed July 5, 1919. Serial No. 308,734.

To all whom it may concern:

Be it known that we, RALPH EHRENFIELD, a citizen of the United States, and a resident of Wilkinsburg, in the county of Allegheny and State of Pennsylvania, and HAROLD G. CALDWELL, a citizen of the United States, and a resident of Wilkinsburg, in the county of Allegheny and State of Pennsylvania, have invented a new and useful Improvement in Mountings for Sewing-Machine Motors, of which the following is a specification.

Our invention relates to driving mechanism for sewing machines or other similar power-operated devices employing an electric motor attached thereto, and it has for its object to provide a structure wherein the machine and the motor are united in a novel manner to form a strong, rugged, compact and inexpensive structure.

It has been customary to drive a sewing machine by means of a separate motor so disposed upon the sewing machine table as to engage the hand wheel and which may be removed when it is desired to close the machine or to mount the motor on the sewing machine head or to permanently and rigidly mount the motor on the base portion of the machine which moves with the head during the closing operation, the motor being disposed in an inoperative unobtrusive position when the machine is closed and being movable to an operative position when open.

Our invention relates specifically to the latter type of machine and consists of a rugged, simple and inexpensive, as well as novel, means for accomplishing the desired result.

For a further understanding of our invention, reference may now be had to the accompanying drawings, Figs. 1 and 2 of which are end and side elevational views, respectively, of a sewing machine provided with a motor mounted in accordance with our invention in its operative position; Fig. 3 is a plan view of the same structure with the motor in its inoperative position; Fig. 4 is a detail view of one portion of the motor-mounting structure shown in the other figures.

Referring to the drawings, in detail, we show a sewing machine comprising a head 1, provided with a laterally extending arm 2

and a hand wheel 3 mounted upon a shaft 4. An electric motor 5 is provided with a drive wheel 6 upon a shaft 7 and is mounted upon a supporting structure 8. The supporting structure 8 comprises a main upright supporting member 9 provided with a base 10 which is bolted or otherwise secured to a base portion 11 of the machine head or to that portion of the table which folds with the machine head. The upper portion 12 of the member 9 (as best shown in Fig. 4) is provided with a slot 13, the central portion of which is arcuate in shape, a portion 14, adjacent the hand wheel of the machine which extends in a vertical direction and a portion 15 at the opposite side thereof which extends in a horizontal direction and under a portion of the arcuate slot, forming a lip 16 therebetween. At the axis of the arc formed by the slot is an opening 17 which receives a pivot pin or bolt 18. Upon the pin 18 is mounted a second supporting member 19 provided with two arms 20 and 21 which support a second pivot pin 22. Upon the pin 22 are pivotally mounted two supporting lugs 23 and 24 with which the frame of the motor 5 is provided. A spring 25 surrounds the pin 22 and engages the lug 23 at one end and the arm 21 at the other end and serves to bias the motor 5 towards the machine, about the pin 22 as an axis. The lug 23 is provided with a pin 26 which extends into the slot 13 in the member 9.

Having thus described the details of a structure embodying our invention, the operation thereof is as follows. When the motor is in its operative position, as shown in Fig. 2, the member 19 is in alignment with the portion 12 of the member 9, the pin 26 is in the vertical portion 14 of the slot 13 in the member 12, and the motor 5 is held directly in front of the head of the sewing machine. When it is desired to move the motor to its inoperative position, in order to close the machine, the motor 5 is pulled away from the machine head a short distance so as to raise the pin 26 into the upper portion of the slot 14, the motor is then turned about the pin 18 as an axis until it is substantially 90° from its former position, the pin 26 moving within the arcuate portion 13 of the slot in the member 12. The motor is then released and the spring 25 moves it to a position beside the head 1 and

beneath the arm 2, as best shown in Fig. 3, the pin 26 moving into horizontal portion 15 of the slot in the member 12.

It will be understood that the spring 25 continually exerts a force tending to turn the motor about the pin 22 as an axis and that the pin 26, riding within the slot, prevents this action except when the pin is at the one or the other end of the slot. If the 10 pin 26 is at the end 14 of the slot, the spring causes it to move to the lower portion thereof, allowing the drive wheel to engage the hand wheel of the motor and when it is at the end 15 of the slot, it moves into the inner end of the horizontal portion of the slot, allowing the spring to move the motor under the arm 2 and beside the head 1.

It will be understood that this same result could be accomplished by mounting the 20 support 9 upon the head 1 of the sewing machine or upon any other rigid portion that is movable therewith.

Throughout this specification and in the 25 claims, the term "head" refers to the upright portion of supporting standards of the driven machine.

While we have shown but one form of our invention, it will be understood, by those skilled in the art, that it is not so limited 30 but is susceptible of various minor changes and modifications without departing from the spirit thereof and we desire, therefore, that only such limitations shall be placed thereupon as are imposed by the prior art 35 or are specifically set forth in the appended claims.

We claim as our invention:

1. In combination with a driven machine comprising a driven wheel, a motor provided with a drive wheel adapted to engage said driven wheel, and a support for said motor comprising means for permitting movement thereof with respect to said driven machine in a plurality of planes disposed at an angle to each other, and means for defining the path of movement of said motor.

2. In combination with a driven machine comprising a driven wheel, a motor provided with a drive wheel adapted to engage said driven wheel, and a support for said motor comprising means for permitting movement thereof with respect to said driven machine about a plurality of axes disposed at an angle to each other, and means for limiting the movement of said motor to a predetermined path.

3. A driven machine comprising a driven wheel, a movable electric motor provided with a drive wheel, a support for said motor comprising a member provided with a slot, and means projecting into said slot whereby movements of said motor are defined and limited, said means being disposed 65 at different positions in said slot when said

motor is in its operative and in its inoperative positions.

4. A driven machine comprising a driven wheel, a movable electric motor provided with a drive wheel, a support for said motor comprising a member provided with a slot, and means projecting into said slot whereby movements of said motor are defined and limited, said means being disposed at one end of said slot when said drive wheel engages said driven wheel and at the other when said motor is in its inoperative position.

5. A driven machine comprising a driven wheel, a movable electric motor provided with a drive wheel, a support for said motor comprising a member provided with a slot, and means mounted on said motor projecting into said slot whereby a possible movement path for said motor is predetermined.

6. A supporting device comprising a member provided with a substantially arcuate slot, a pin disposed at the axis of the arc formed by said slot, a member pivotally mounted upon said pin and having a projection to engage said slot, whereby the possible movements of said means are defined and limited.

7. A driven machine comprising a head provided with an arm and having a driven wheel mounted thereon, said head being mounted upon a supporting base, an electric motor provided with a drive wheel, and a separate upright supporting member rigidly mounted upon said base, an additional supporting member pivotally mounted upon said first mentioned supporting member so as to move in a plane parallel to the axis of the driven wheel, and a member supporting said motor and pivotally mounted upon said second mentioned supporting member to move toward and away from said machine.

8. A sewing machine comprising a head provided with an arm and having a driven wheel mounted thereon, an electric motor provided with a drive wheel adapted to engage said driven wheel to drive the same, and means for supporting said motor, said means comprising a member provided with an arcuate slot, a pin disposed at the axis of the arc formed by said slot, a second supporting member pivotally mounted upon said pin, a second pin mounted in said second mentioned supporting member, a third supporting member pivotally mounted thereon and attached to said motor, and a pin mounted in said third supporting member and projecting into the slot in said first mentioned supporting member.

9. A sewing machine comprising a head provided with an arm and having a driven wheel mounted thereon, an electric motor provided with a drive wheel adapted to engage said driven wheel to drive the same, and means for supporting said motor, said

means comprising an upright member provided with an arcuate slot adjacent the top thereof, and a horizontal pin mounted thereon at the axis of the arc formed by said slot and extending in a direction perpendicular to the axis of said driven wheel, a second supporting member pivotally mounted upon said pin, which, in turn, is provided with a pin disposed parallel to the axis of said driven wheel, when in its operative position, and a third member pivotally mounted upon said second mentioned pin and supporting said motor, and a pin mounted on said third member and extending into said arcuate slot.

10. A sewing machine comprising a head provided with an arm and having a driven wheel mounted thereon, an electric motor provided with a drive wheel adapted to engage said driven wheel to drive the same, and means for supporting said motor comprising an upright member provided with an arcuate slot adjacent the top thereof, and a horizontal pin mounted thereon at the axis of the arc formed by said slot and extending in a direction perpendicular to the axis of said driven wheel, a second supporting member pivotally mounted upon said pin, which, in turn, is provided with a pin disposed parallel to the axis of said driven wheel, when in its operative position, and a third member pivotally mounted upon said second mentioned pin and supporting said motor, and a pin mounted on said third member and extending into said arcuate slot, and a spring mounted upon said second mentioned pivot pin for exerting a force upon said motor toward said machine.

11. A sewing machine comprising a head provided with an arm and having a driven wheel mounted thereon, an electric motor provided with a drive wheel adapted to en-

gage said driven wheel to drive the same, and means for supporting said motor comprising an upright member provided with a slot adjacent the top thereof the central portion of which is substantially arcuate in shape having a vertical portion adjacent the driven wheel and having a horizontal portion adjacent the opposite end and extending under a portion of the central portion of the slot, and a horizontal pin mounted thereon at the axis of the arc formed by said slot and extending in a direction perpendicular to the axis of said driven wheel, a second supporting member pivotally mounted upon said pin, which, in turn, is provided with a pin disposed parallel to the axis of said driven wheel, when in its operative position, and a third member pivotally mounted upon said second mentioned pin and supporting said motor, and a pin mounted on said third member and extending into said arcuate slot, and a spring mounted upon said second mentioned pivot pin for exerting a force upon said motor toward said machine.

12. In combination with a driven machine comprising a driven wheel, a motor provided with a drive wheel adapted to engage said driven wheel, and a support for said motor comprising means for permitting movement thereof with respect to said driven machine about two axes disposed perpendicular to each other, said support comprising means for limiting the movement of said motor to a predetermined path.

In testimony whereof, we have hereunto subscribed our names this 1st day of July, 1919.

RALPH EHRENFIELD.
HAROLD G. CALDWELL.
